[57] **CLAIM**

The ornamental design for a pressed coffee tablet, as shown and described.

DESCRIPTION

FIG. 1 is a side elevational view of a pressed coffee tablet showing my new design, the undisclosed side being the same;

FIG. 2 is a side elevational view of a second embodiment of FIG. 1, the undisclosed side being the same; and,

FIG. 3 is a bottom plan view of the pressed coffee tablet of FIG. 1, the pressed coffee tablet of FIG. 2 having the same bottom view.

It is understood that the top of both embodiments of the article is plain and unornamented.
